COMBINED FILM RECORDER AND SCANNER UNIT FOR DATA PROCESSING

Seton Cottier, Woodstock, and Ronald I. Conway, Kingston, N.Y., assignors to International Business Machines Corporation, New York, N.Y., a corporation of New York

Filed Sept. 8, 1964, Ser. No. 81,624

Term of patent 14 years

(Cl. D26—5)

FIG. 1

FIG. 2

FIG. 1 is a perspective view of a combined film recorder and scanner unit for data processing showing our new design, showing the front, top and one end thereof; and

FIG. 2 is a perspective view thereof showing the rear, top and other end thereof.

We claim:

The ornamental design for a combined film recorder and scanner unit for data processing, substantially as shown.
